UNITED STATES PATENT OFFICE.

JACOB A. SMITH, OF CHICAGO, ILLINOIS, ASSIGNOR TO RELIABLE ELECTRIC COMPANY,
OF CHICAGO, ILLINOIS, A CORPORATION OF ILLINOIS.

SUPPORT FOR ELECTRIC-LAMP SOCKETS.

1,105,855.

Specification of Letters Patent.

Patented Aug. 4, 1914.

Application filed January 16, 1913. Serial No. 742,399.

To all whom it may concern:

Be it known that I, JACOB A. SMITH, a citizen of the United States, residing at Chicago, in the county of Cook and State 5 of Illinois, have invented a certain new and useful Improvement in Supports for Electric-Lamp Sockets, of which the following is a full, clear, concise, and exact description, reference being had to the accompanying 10 drawings, forming a part of this specification.

My invention relates to an improved lamp socket support for electric lamps, by means of which an electric lamp may be temporarily held and supported in any desired position and readily moved from one place to another and further that it may be attached or supported from different objects, such as shelves, table tops, etc., by means of a 20 special form of spring clamp connected with the socket support.

The several drawings illustrating my invention are as follows:

Figure 1 shows the socket support and 25 clamp in perspective view supporting a lamp socket from a shelf. Fig. 2 is a top view of the socket supporting portion of the device.

Similar numerals refer to similar parts 30 throughout the several views.

As shown in the drawings the device consists of a socket clamp comprising a ring-shaped band 1, of spring metal open at one side. The band 1 is secured by a strip of 35 similar material 2, to the convolutions 3 of a spring 4, formed of cylindrical wire or rod of spring material of suitable diameter. The convolutions 3 are so disposed relatively to the member 2, that one convolution 40 is upon one side of said member while two other convolutions are upon the opposite side of said member, thus securely holding the member 2 in place upon the spring 4, and therefore securely supporting the socket clamp 1 therefrom as well as socket 45 5 and lamp 6 when the latter is in position in the socket. The spring band 1 and the member 2 may be secured together in any desired manner, as for example by rivets 7, 50 as indicated. The ends of the clamp 4 opposite to the convolutions 3, are bent as shown at 8 and 9 so as to lie adjacent to each other and project in opposite directions, and are extended sufficiently so that 55 the rings 10 and 11 formed in substantially

parallel planes approximately at right angles to the portions 8 and 9, are normally moved toward each other by the spring of the clamp 4 and particularly by the spring of the convolutions 3 of said clamp. As a 60 result the main members of the clamp 4 between the portions 8 and 9 and the convolutions 3 may be engaged and grasped by the hand so that the pressure exerted upon these main members will force the rings 10 65 and 11 away from each other so that they may be placed upon opposite sides of the particular article or thing to which it is desired to secure the electric lamp. In Fig. 1 of the drawings this article is assumed to be 70 a shelf 12, the ring 11 being disposed above and the ring 10 below said shelf, and the spring of the clamp 4, holds these rings in engagement with the top and bottom of the shelf with sufficient force so that the 75 lamp socket and lamp are securely held in the desired position. When it is desired to remove the lamp from the shelf 12 all that is necessary is to press the main members of the clamp 4, toward each other, thus freeing the rings 10 and 11 from the shelf, for which condition the clamp and socket support together with the socket and lamp may readily be removed.

The rings 10 and 11 have preferably 85 formed in them offsets 13 and 14, the inner surfaces of which are provided with teeth as indicated to engage securely a round rod or bar when it is desired to attach the clamp to such a structure. These offsets are so 90 formed that they do not interfere with the body portions of the rings, clamping flat surfaces when said surfaces are engaged to support the lamp and socket.

It will at once appear that the socket support above described may be attached to any object or article whether flat or round which can be inserted between the rings 10 and 11 when the latter are separated from each other as described above.

While I have shown my invention in the particular embodiment described above it will be understood that I do not limit myself to this exact construction, but on the other hand may employ other parts constructed and operating in substantially the same way for accomplishing the results contemplated.

What I claim is:

1. In a support for an electric lamp socket,

the combination of a support for the socket, a member secured to said support, a spring clamp having a plurality of convolutions formed at one end upon opposite sides of 5 said member to secure it to said clamp, said clamp consisting of a bent cylindrical wire or rod of spring material, the ends of which are conformed into opposite clamping surfaces tending to move into engagement with 10 each other by the spring of the clamp and disposed so that they may be moved from each other by pressure exerted upon the clamp.

2. In a support for an electric lamp socket, 15 the combination of a clamping device of spring material having its ends conformed into opposition clamping portions, a plurality of convolutions formed in its middle portion, said convolutions and said clamping 20 portions being connected by main members of the spring clamp, said main members so disposed that pressure upon them will move the said clamping portions away from each other, and a socket support engaging the 25 outer portions of the convolutions.

3. In a support for an electric lamp socket, the combination of a clamping device of spring material having its ends conformed into opposite clamping portions, a plurality 30 of convolutions formed in its middle portion, said convolutions and said clamping portions being connected by main members of the spring clamp, said main members so disposed that pressure upon them will move 35 the said clamping portions away from each other, and a socket support secured to the convolutions at a point farthest from the clamping portions.

4. In a support for an electric lamp socket, 40 the combination of a clamping device of spring material having opposite clamping portions formed upon its ends, the central portion of said clamping device being formed into a spring portion tending to hold 45 said clamping device in clamping position, said device also having main members con-

necting said spring portion with said clamping portions and so disposed that pressure upon them will move said clamping portions away from each other against the tendency 50 of said spring portion, and a socket support carried by said spring portion.

5. In a support for an electric lamp socket, the combination of a clamping device of 55 spring material having opposite clamping portions formed upon its ends, the central portion of said clamping device being formed into a spring portion tending to hold said clamping device in clamping position, said device also having main members connecting said spring portion with said clamping portions and so disposed that pressure upon them will move said clamping portions away from each other against the tendency of said 60 spring portion, a socket support carried by 65 said spring portion, and off-sets in said clamping portions extending outwardly therefrom to engage a rod between them.

6. In a support for an electric lamp socket, the combination of a clamping device of 70 spring wire bent at substantially its middle portion to form a spring and having oppositely disposed clamping portions formed upon its ends, said wire being formed into main members connecting said clamping 75 portions with said spring portion and so disposed that pressure upon said main members will move said clamping portions away from each other against the tendency of said spring portion, a socket support carried by 80 said clamping device and off-sets in said clamping portions extending outwardly therefrom to receive between them a rod, the inner surfaces of said off-sets being provided with teeth to grip said rod. 85

In witness whereof, I have hereunto subscribed my name this 14th day of January, A. D. 1913.

JACOB A. SMITH.
